UNITED STATES PATENT OFFICE.

WILLIAM BERRY, OF CLEVELEYS, NEAR BLACKPOOL, ENGLAND.

OBTAINING OF GRAIN AND LIKE EFFECT IN PAINTING.

1,416,325.

Specification of Letters Patent. Patented May 16, 1922.

Application filed December 16, 1919. Serial No. 345,423.

To all whom it may concern:

Be it known that I, WILLIAM BERRY, a subject of the King of Great Britain and Ireland, and resident of Rossall Road, Cleveleys, near Blackpool, England, decorative painter, have invented certain new and useful Improvements Relating to the Obtaining of Grain and like Effects in Painting, of which the following is a specification.

10 This invention relates to the obtaining of grain and like effects in painting, and has for its object to provide an improved process as hereinafter described and claimed for obtaining such effects in an efficient and ready 15 manner.

According to my invention, the surface to be painted and grained, after preparation in the usual manner, is provided with a ground or base colour, but before the surface colour 20 is painted over the base colour, I groove the wood or material being painted with disc or like rotary cutters, having, if desired, cross cuts on their peripheries to give any particular cross markings required. The grooving 25 of the surface having been accomplished, the surface coat of paint is applied thereto. The wood or material is then wiped whilst the surface paint is still wet, so that such paint remains only in the hollows or grooves 30 but is removed from the projecting ribs between the grooves. I thus obtain a very effective graining of the wood and can produce any desired markings.

Figure 1 is an end view and Figure 2 a 35 front view of the graining tool used in the carrying out of my invention. Figure 3 illustrates one of the discs of the tool.

The tool or instrument I prefer to employ for grooving purposes, is of the form illustrated at Figure 1 and comprises a shaft or

handle *a* with a pin or spindle *b* supported thereon carrying a plurality of discs *c*, each free upon the spindle, washers or distance pieces *d* of any desired thickness being provided between the discs or between one set of 45 discs and the next set on the one spindle. The discs may have cross cuts upon their peripheries to give irregular cross markings in the grain such as are found in the oak or like wood, of which the grain is being copied. 50 Figure 3 shows one form of cutter disc *c*. The discs are of small diameter so that the operator can work into the corners and borders of the articles being painted and grained. The number of discs in the tool or instrument may be varied to suit any particular 55 services or requirements.

I may also use a tool such as is shown at Fig. 2.

Tools such as before described and illustrated have heretofore been proposed for graining wood.

Having now described my invention what I claim as new and desire to secure by Letters Patent is:—

Process for producing grain and like effects on wood or other material, characterized in this, that the wood or material, to be grained is first provided with a ground color which is allowed to set, secondly has grooves 70 formed therein by disc or like cutters to correspond with the pattern of the desired grain markings, thirdly has a surface coat of paint applied to the grooved wood, and fourthly has the surface paint removed by 75 wiping, except from the grooves in which it remains as set forth.

In testimony whereof I have signed my name to this specification.

WILLIAM BERRY.
